(57) **CLAIM**

The ornamental design for a wall arm ring toss game, as shown and described.

DESCRIPTION

FIG. 1 is a perspective view of a wall arm ring toss game in an open configuration in accordance with the present invention;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a perspective view of the wall arm ring toss game in a closed configuration in accordance with the present invention;

FIG. 9 is a front elevation view thereof;

FIG. 10 is a rear elevation view thereof;

FIG. 11 is a top plan view thereof;

FIG. 12 is a bottom plan view thereof;

FIG. 13 is a left side elevation view thereof; and,

FIG. 14 is a right side elevation view thereof.

The broken lines in the drawings depict portions of the wall arm ring toss game that form no part of the claimed design. The wall arm ring toss game is shown with a symbolic break in the length of each side. The appearance of any portion of the article between the break lines forms no part of the claimed design.

1 Claim, 9 Drawing Sheets
